(57) **CLAIM**

The ornamental design for a golf tee adaptor, as shown and described.

DESCRIPTION

FIG. 1 is a top perspective view of a golf tee adaptor showing my new design;

FIG. 2 is a bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a scaled-down front perspective view showing the design in association with a golf tee;

FIG. 10 is an exploded perspective view of the golf tee and the golf tee adaptor in FIG. 9; and,

FIG. 11 is an exploded perspective view showing the design in association with a broken golf tee.

The broken lines showing the golf tee in FIG. 9 and FIG. 10 and showing the broken golf tee in FIG. 11 are included for the purpose of illustrating environmental structure and forms no part of the claimed design.
